UNITED STATES PATENT OFFICE.

ISAAC H. GOODMAN, OF PHILADELPHIA, PENNSYLVANIA.

DESIGN FOR TEXTILE FABRIC.

SPECIFICATION forming part of Design No. 28,516, dated April 26, 1898.

Application filed February 4, 1898. Serial No. 669,153. Term of patent 31 years.

To all whom it may concern:

Be it known that I, ISAAC H. GOODMAN, a citizen of the United States, residing in Philadelphia, Pennsylvania, have invented a new

5 and original Design for a Textile Fabric, of which the following is a specification.

My design for textile fabric is fully shown in the accompanying drawing, which represents a view of a piece of the fabric.

10 The fabric is intended mainly for hat or bonnet trimming and is composed of a series of threads secured together and arranged at irregular intervals and crossing each other at irregular distances and at different angles, the threads in some parts of the fabric

being bunched closely side by side and in other parts being single, this disposition of the threads constituting the essential feature of the design.

I claim—

20 The design for a textile fabric, substantially as described and as shown in the accompanying drawing.

In testimony whereof I have signed my name to this specification in the presence of 25 two subscribing witnesses.

ISAAC H. GOODMAN.

Witnesses:

MURRAY C. BOYER,
JOS. H. KLEIN.
